UNITED STATES PATENT OFFICE.

JOHN A. MATTSON, OF CHICAGO, ILLINOIS, ASSIGNOR OF ONE-HALF TO ANDREW S. NOJD, OF CHICAGO, ILLINOIS.

ROOF CARRIAGE.

1,412,060.

Specification of Letters Patent. Patented Apr. 11, 1922.

Application filed December 11, 1918. Serial No. 266,288.

To all whom it may concern:

Be it known that I, JOHN A. MATTSON, a citizen of Sweden, residing at Chicago, in the county of Cook and State of Illinois, 5 have invented certain new and useful Improvements in Roof Carriages, of which the following is a specification.

This invention relates to improvements in roof carriages and its chief object is to 10 provide a carriage adapted to travel over inclined building roofs to carry building material or other material from place to place upon the roof, or from side to side, end to end of the roof, etc. The carriage is so 15 constructed and assembled as to permit its adjustment to suit roofs of various inclinations or pitches and to permit its adjustment in other ways, to be hereinafter set forth, to suit the general lay of the roof. 20 With the foregoing and other objects in view the invention consists in the combination and arrangement of parts to be hereinafter fully described, pointed out in the appended claims and illustrated in the accompanying drawings which form a part 25 of this specification and in which—

Fig. 1 is a front view of my improved roof carriage illustrating its application.

Fig. 2 is a side view of Fig. 1.

Fig. 3 is a top plan view of Fig. 1.

Fig. 4 is an enlarged plan view of the 30 carriage itself.

Fig. 5 is a side view of Fig. 4, partly in section, the sectioned portion being taken on line 5—5 of Fig. 4.

Like reference characters denote 35 corresponding parts throughout the several views.

The reference numeral 1 denotes inclined roof beams transversely of which the channel beams 2 extend. My roof carriage is 40 adapted to travel over the roof upon the channel beams 2. The carriage comprises an outer main frame 3 substantially V-shaped, the closed end of the frame being offset. The sides of the frame 3 are formed 45 with the longitudinal slots 4 through which the set screws 5 extend that adjustably connect the upper ends of the brace bars 6 to said frame, the lower ends of said bars 6 being connected by set screws 7 to the lower 50 sections 8 of the legs 8, 9, said leg sections telescoping one into the other and being adjustably connected together by set

screws 10, the upper leg-sections 9 directly supporting the open end of the frame 3. 55 The lower leg sections 8 are directly bolted to and supported by an elongated link-shaped casting 11 formed with a longitudinal central slot 12, said casting in the ends of its longitudinally slotted portion 60 being provided with the flanged wheels 13, adapted to run over the channel beams 2. Adjacent each wheel 13 a pivot 14 is carried by the casting 11 and upon said pivot an angle piece 15 is carried which extends below the flange of the wheel 13 and is disposed upon the opposite side of the beam 2 with respect to the wheel flange. The purpose of the said angle piece is to prevent the wheel riding off the beam. The angle 65 piece 15 may be moved from its position shown in full lines, Fig. 2, to its position shown in dotted lines to accommodate the wheels of the carriage to beams 2 of greater or less distance apart in a manner to be 70 more fully described hereinafter.

A runway 16 comprising angle iron tracks is disposed inside the frame 3 and supported by suitable braces 17 which connect it with said frame, said runway being formed with longitudinal slots 19, 20, similar to slots 4 of frame 3, and bolts 21, 22 disposed, respectively, in said slots connect the runway to a sliding auxiliary frame 18, said frame 18 in its sliding movement moving the bolts 21, 22 back and forth in the slotted portions 19, 20 of the runway. The runway at one end is connected directly to the sides of the frame 3 and at its outer end it is supported by the inclined braces 16^a which run to the link 11. The bolts 22 carry a casting 23 which extends transversely of the auxiliary frame and which is connected to one end of said frame by the axis 24 of a flanged wheel 25 adapted to run upon the channel beams 2. The purpose of the sliding auxiliary frame 18 is to adjust the wheel 25 relatively to the wheels 13 to permit the carriage to travel over channel beams 2 of varying distances apart. To the end of the auxiliary frame adjacent the wheel 25 I secure an 95 angular guard 26 which projects below the flange of the wheel into close proximity to the channel beam and serves to prevent the wheel from riding off the beam. The guards 15, 26 cooperate with each other to 100 retain the wheels upon the beams 2 and 105

guard 15 may be moved into dotted position, Fig. 2, to accommodate beams 2 having wide treads.

The frame 3 is kept level regardless of the relative differences in height of the beams 2 over which the carriage is running by means of the telescoping legs 8, 9 which, obviously, are readily adjusted to raise or lower the open end of the frame. The material to be transported upon the carriage is placed directly upon the frames 3, 18, or either of them, and the carriage then manually pushed along the roof by one or two men who walk upon the roof beams 15 balancing themselves by means of the carriage. The work carried may be piled against the arms 27 supported by the braces 28 which adjustably secure them to the frame 3 as shown.

20 What is claimed is:—

1. In a carriage, a V-shaped frame, legs adjustably supporting the open end of said frame, a wheeled carrier for said legs, a

sliding auxiliary frame carried inside said V-shaped frame, and a wheel for said sliding auxiliary frame, said wheel being disposed at the closed end of said V-shaped frame.

2. In a carriage, a main frame, telescoping sectional legs supporting one end of said main frame, a wheeled support for said legs, a runway arranged within said main frame, a sliding auxiliary frame operatively supported by said runway, a wheel arranged at one end of said sliding auxiliary frame, and a work rest adjustably carried by said main frame.

In testimony that I claim the foregoing as my own I have hereto affixed my signature in the presence of two subscribing witnesses.

JOHN A. MATTSON.
